UNITED STATES PATENT OFFICE.

HEMAN A. BARNARD, OF MOLINE, ILLINOIS, ASSIGNOR TO THE BARNARD & LEAS MANUFACTURING COMPANY, OF SAME PLACE.

FLOUR-PACKER.

SPECIFICATION forming part of Letters Patent No. 398,999, dated March 5, 1889.

Application filed March 3, 1888. Serial No. 266,018. (No model.)

To all whom it may concern:

Be it known that I, HEMAN A. BARNARD, of Moline, in the county of Rock Island and State of Illinois, have invented certain new and useful Improvements in Flour-Packers; and I do hereby declare that the following is a full, clear, and exact description thereof, reference being had to the accompanying drawings, and to the letters of reference marked thereon, which form part of this specification, in which—

Figure 1 is a front elevation of my improved flour-packer. Fig. 2 is a side elevation of the same. Fig. 3 is a side elevation showing a modification. Fig. 4 is a view of the gearing-frame detached. Figs. 5 and 6 are details.

This invention relates to improvements in flour-packers; and its objects are to provide improved mechanisms for starting the packer and for automatically stopping the same, and, further, to improve the supports of the gearing of the packer. These objects I attain by the present invention, which consists in the novel construction and arrangement of parts hereinafter described, illustrated in the drawings, and particularly specified in the claims hereto appended.

Referring to the drawings by letter, A designates the main frame of the packer, consisting of two vertical uprights, *a a*, suitably connected at top and bottom, which may be provided with any suitable guides for a vertically-reciprocating platform, *W*, hereinafter referred to. At the top of frame A is mounted a rectangular frame, *B*, made of cast metal. This frame has bearings *b b* cast integral on its upper and lower rails and forming half of the journal-boxes of the vertical auger or packer shaft *C*, which is confined in bearings *b b* by half-boxes *c c*, bolted to frame *B*, as shown.

At one end of frame *B* is formed an offset arch, *D*, provided with a bearing, *d*, which stands at right angles to bearings *b b* and corresponds with a similar bearing, *E*, formed on the adjoining end rail of frame *B*, as shown, the latter bearing, *E*, however, being lengthened, as shown, to properly align and support a short shaft, *F*, which is retained in bearing *E* by a cap, *e*, bolted to frame *B*, as shown. The shaft *F*, it will be seen, stands at right

angles to shaft *C*, and bears on its inner end a bevel-gear, *f*, meshing with a gear on shaft *C*. On the outer end of shaft *F* is mounted the cup-wheel *g* of a friction-clutch, *G*, hereinafter referred to. Gear *f* and wheel *g* are set on shaft *F*, so that it is kept from any longitudinal play in bearing *E*.

H designates a shaft, one end of which is supported and journaled in bearing *d*, being retained therein by a cap, *h*, as shown. Shaft *H* lies in line with shaft *F*, and bears on its inner end, within offset *D*, the movable disk *g'* of the friction-clutch *G*, as shown, which is properly mounted on shaft *H*, so that it can be engaged with cup-wheel *g* and impart motion to shaft *F*. The other end of shaft *H* may be journaled in any suitable support in the building where the packer is mounted, and motion is imparted to said shaft by any proper power. The shafts *F* and *H* constitute a sectional counter-shaft by which the packer is operated.

I indicates a movable arch bolted to the upper rail of frame *B* through openings *i i* therein, so that the arch will stand directly over the upper end of shaft *C*.

J designates an oil-cup fitted on the upper end of shaft *C*, and *j* is a set journal-screw mounted in arch *I* and entering cup *J*, so that the shaft *C* will be kept from rising in its bearings on frame *B*. Cup *J* can be filled with oil to prevent wear of the parts *J* and *j*.

i' i' are openings in the lower rail of frame *B*, corresponding in position to the openings *i i*, so that, if desired, frame *B* can be reversed and shafts *G* and *F* be on the left-hand side of the machine.

K K' are similar arms or studs projecting rearwardly from the arch *D* at equal distances from bearing *d*. Stud *K* in this instance forms the pivotal support for a lever, *L*, the bifurcated upper end of which loosely engages the hub of the movable disk *g'* of clutch *G*, as usual, so that by oscillating lever *L* the parts *g* and *g'* may be engaged or disengaged. When the frame *B* is reversed, lever *L* is mounted on stud *K'*. The lower end of lever *L* is pivotally connected to one end of toggle-lever *M*, the other arm of which is pivoted to a proper keeper on the

main frame A, and this toggle-lever M is pivotally engaged at its joint with a depending rod, N, by which the toggle-lever is opened or extended.

5 m designates a coiled spring connected with the upper end of rod N and to a point on the frame B, and serving to retract the rod after it has been depressed, and thereby retract the toggle-lever. It will be observed that when the toggle-lever is extended the lever L is shifted so as to throw the parts of the friction-clutch into engagement and keep them so until the lever is released and retracted, so that by depressing or elevating 10 rod N the packer will be set in operation or stopped. The rod N extends downward nearly to the base of the machine and is attached to an angular dog, O, pivoted vertically through a keeper, P, secured to the main frame. When rod L is depressed, the dog O is engaged by its tooth with the side of keeper P, and the dog has an inwardly-projecting bent arm, o, which is adapted to be struck by 15 a lug, y, on the platform W and knocked outward, disengaging the keeper P and releasing rod L. The rod N is connected with a short hand-lever, l, pivoted to the upright a above keeper P, by which the rod can be depressed when desired, or after it has been released by the platform.

The platform W, which is adapted to support a barrel or sack while being filled, is operated by means of a chain, Q, which passes under friction-pulleys on the top rail, w, of the 20 platform-support, and is attached to grooved cone-drums q on a horizontal shaft, R, suitably journaled on the main frame at the rear thereof and extending outward on the side below shaft H, and receiving motion from a pulley, s, on the latter shaft by a belt, S, and a pulley, r, on shaft R, as shown. Belt S is made very slack, however, so that it has to be tightened in order to operate shaft R. This is accomplished by means of a tightener, T, composed of a bifurcated angular frame mounted 25 on shaft R and embracing pulley r, and carrying in its upper end a friction-pulley, t, as shown. The lower end of frame T is pivotally connected with the upper end of a stiff 30 push-rod, U, which is operated by a treadle, u, secured to the floor at the side of frame A, as shown, in convenient position to be operated by foot. The pulley t stands within belt S, which is preferably crossed and bears against 35 the inner face thereof, as shown.

The belt S is used solely to cause the lifting of platform W, and its descent is by gravity, regulated, however, by means of a friction-wheel, V, on shaft R, surrounded by a friction-band, v, one end of which is fixed to the main frame, and the other end is connected to an oscillating pivoted scale-beam lever X, which is provided with an adjustable weight, x, as shown, by which the amount of friction on 45 wheel V can be regulated, and thereby the power required to depress platform W.

In order to release the friction-pulley when

the belt S is tightened, I connect the rear end of the lever X by a rod, Y, with the front end of treadle u, so that the friction-band v will 70 be loosened simultaneously with the tightening of the belt S, and will be tightened simultaneously with the loosening of said belt.

Z designates a metal cylinder properly supported on frame A above platform W and surrounding shaft C, which latter is provided within the cylinder with a worm or worm-fingers, which force the material down in said tube. The upper end of cylinder Z is provided with an enlarged receiving mouth or 80 funnel, z, into which the material is fed.

While the rod N can be readily depressed by hand, as described, yet, in order to expedite the working of the packer, I employ another means for depressing the rod from treadle u. 85 To do this a chain, L', is attached to rod N, above the dog O, and passed over bracket-piece M', attached to one upright a, so as to keep the chain from interfering with the dog and cause the chain when depressed to draw 90 rod N inward, and thereby cause the automatic engagement of dog O with its keeper. The outer end of the chain is attached to the treadle u, as shown.

In operation a barrel or sack to be filled is 95 placed upon platform W. Treadle u is depressed by the foot, simultaneously causing the tightening of belt S and the depression of rod N. Belt S causes shaft R to rotate, winding chain Q and lifting platform W, with 100 the barrel or sack, into which cylinder Z enters and delivers the material. The depression of rod N engages dog O, causing the closing of parts g and g' of clutch G, so that shaft C is rotated and begins to forcibly feed the 105 flour through cylinder Z. As soon as platform W is sufficiently elevated, the treadle is released, stopping the rotation of shaft R and applying the brake thereto. The weight on the brake-lever is so adjusted as to overcome 110 the gravity of the platform and require a certain downward degree of pressure to be expended upon the platform to lower it. This pressure is imparted by the worm on shaft C as the material is packed, so that the barrel 115 is filled properly. The cone-drums on which chain Q is wound are so graduated as to diminish the leverage of the chain on shaft R as the platform descends, and thereby compensate for the weight of the material in the 120 barrel. When the platform descends, the lug y is so arranged as to strike the dog O and cause it to disengage the keeper, and the parts acting as already described cause the disengagement of the parts g and g' of clutch G 125 from shaft F and the stoppage of shaft C, and consequently of the packing operation.

Having described my invention, what I claim is—

1. In a packer, a metal frame having bearings cast integral with it for the support of the auger and driving shafts, and a detachable arch, constructed substantially as described, attached to said frame and adapted

to keep the auger-shaft from rising out of place, said frame being provided with bolt-holes at the upper and lower side and made reversible, whereby the driving-shaft may be 5 made to extend to either side and the arch attached in proper position when reversed, substantially as described.

2. The combination of the sectional counter-shaft with the shaft R, carrying cones 10 drums, a friction-wheel, and a pulley, with the belt S, tightener T, friction-band v, lever X, rods U and Y, and treadle u, whereby the belt S can be tightened simultaneously with the loosening of the friction-band, and vice 15 versa, substantially as described.

3. The combination of frame A, the metal frame B thereon, the auger-shaft and sectional counter-shaft supported thereon, and the friction-clutch G on said counter-shaft, 20 with the bifurcated lever for operating said clutch pivoted on a lug projecting from frame B, the toggle-lever M and rod N, for actuating said clutch, and the dog O on said rod, and keeper P on frame A, for holding rod N to 25 keep the clutch engaged, substantially as described.

4. The combination of the auger-shaft, the sectional counter-shaft provided with a friction-clutch, and a vertically-reciprocating 30 platform, with the shaft R and chains for lifting said platform, the belt S and pulleys for transmitting motion from the counter-shaft to shaft R, and mechanism, substantially as described, for simultaneously tightening belt S, 35 to cause the raising of the platform and to operate the friction-clutch to start the shaft, substantially as described.

5. The combination of the auger-shaft, the sectional counter-shaft for driving the same, 40 the friction-clutch on said counter-shaft for connecting its parts, and the vertically-reciprocating platform, substantially as described, with the lever for operating said friction-clutch, the toggle-lever, and spring-controlled 45 rod for operating said lever, and the dog O on said rod engaging a keeper, P, on the main frame when the rod is depressed, to keep the clutch engaged and adapted to be struck by a lug on the movable platform as the latter 50 descends, and to be released, thereby permitting the disengagement of said clutch, substantially as set forth.

6. The combination of the auger-shaft, the sectional counter-shaft connected by a friction-

clutch, and a vertically-reciprocating platform 55 to carry the receptacle to be filled, with the bifurcated lever engaging said clutch, toggle-lever M, and spring-controlled rod N, for operating said clutch, the dog O on said rod, for engaging a keeper on the main frame, and 60 the devices, substantially as described, for depressing said rod to keep the clutch engaged, substantially as set forth.

7. The combination of the sectional counter-shaft and its clutch G, the shaft R, receiving 65 motion from said counter-shaft by a belt, S, and operating the movable platform, with the lever L, toggle M, and rod N, for actuating the clutch, the tightener T for belt S, and the connections of rod N and tightener with a 70 treadle, whereby the platform can be elevated and the packer started simultaneously, substantially as specified.

8. The combination of the sectional counter-shaft having a friction-clutch, G, for connecting its parts and driving the auger-shaft, the movable platform W, shaft R, having friction-wheel V and receiving motion from the counter-shaft by a slack belt, S, when the latter is tightened, with the mechanism for simultaneously closing clutch G, tightening belt S, and loosening the friction-band around pulley V, substantially as specified.

9. The herein-described frame B, having an offset arch, D, and cast with bearings b b for 85 the auger-shaft and bearings E and d for the counter-shaft, and having lugs K K' on arch D, and openings i i' i', and the arch I, bolted to said frame, substantially as set forth.

10. The combination of frame A and reversible frame B thereon, having bearings formed in it for the auger-shaft and counter-shaft, and having opposite lugs, K K', with the auger-shaft C, shaft F, supported in frame B and imparting motion to shaft C, and the 95 shaft H, having one journal in frame B, and engaging shaft F by a friction-clutch, G, and the lever pivoted on one of the lugs of frame B, for operating said clutch, substantially as and for the purpose specified.

In testimony that I claim the foregoing as my own I affix my signature in presence of two witnesses.

HEMAN A. BARNARD.
